DESIGN FOR A BOTTLE

Davis Factor, Los Angeles, Calif., assignor to Max Factor & Co., Los Angeles, Calif., a corporation of Delaware

Application April 8, 1935, Serial No. 56,263

Term of patent 14 years

To all whom it may concern:

Be it known that I, Davis Factor, a citizen of the United States, residing in the city and county of Los Angeles, State of California, have invented a new, original, and ornamental Design for a Bottle, of which the following is a specification, reference being had to the annexed drawing, forming a part thereof.

The drawing shows a bottle, including the cap, embodying my new and ornamental design. In the drawing:

Fig. 1 is a front elevational view;
Fig. 2 is a side elevational view; and
Fig. 3 is a plan showing the elliptical base.

I claim:

The ornamental design for a bottle, as shown.

DAVIS FACTOR.
